UNITED STATES PATENT OFFICE.

NORMAN C. DAVIS, OF PERTH AMBOY, NEW JERSEY, ASSIGNOR TO GENERAL CABLE CORPORATION, OF NEW YORK, N. Y., A CORPORATION OF NEW JERSEY.

STRANDED SECTOR-SHAPED CONDUCTOR.

Original application filed April 20, 1927, Serial No. 185,096. Divided and this application filed March 31, 1928. Serial No. 266,357.

This application is a division of application filed April 20, 1927, Serial No. 185,096, which is itself a continuation in part of an application filed Oct. 25, 1924, Serial No. 5 745,883.

My invention relates to the making of sector-shaped conductors for multiple-conductor cables, and consists in method of production.

It is advantageous, in the making of multiple-conductor cables, particularly those of 10 large size, that the conductors be composed, each of a number of smaller wires, stranded together in helical twist. A cable whose conductors are so composed is flexible in far 15 greater degree than a cable whose conductors consist, each of a single solid wire.

In the making of sector-shaped conductors (a shape advantageous, in that a cable of given circular mileage or cross section may 20 be made of relatively small over-all dimensions) the formation of the individual conductor out of an assembly of small wires presents peculiar difficulties. If the sector shape be attained by a particular grouping of the 25 wires, then stranding (that is to say, helical winding of the wires about one another or about a common axis) becomes impossible. The shape-giving wires must extend straight away through the length of the conductor. 30 Manifestly a conductor so composed, with wires extending straight away throughout its length, is far less flexible, whether under cross-bending or under torsion, than a compound conductor whose constituent wires are 35 stranded or spiraled in a helix. Furthermore, a compound conductor whose body is built up of wires extending straight away throughout its length will, when bent or twisted, tend to lose its characteristic and important sector 40 shape; its component wires will tend to become displaced; the conductor as a whole will tend to assume circular cross-sectional form—this in far greater degree than if the constituent wires were stranded or spiraled.

If the compound sector be built up by binding a core bundle about with one or more layers of stranded (that is to say, helically wrapped) wires, the core bundle itself being made up of parallel straight-away wires of 45 equal or of diverse diameters, grouped to sector shape in cross section, or otherwise made up, then, in consequence of the rounding of the angles incident to the wrapping on of the enveloping layer or layers, the sector

shape of the enveloped core is seriously compromised, and the advantages sought are 55 measurably unattained. This rounding of the corners increases directly with the number of binding layers applied.

If the sector shape be attained by rolling 60 to sector-shape a conductor composed of a plurality of wires initially stranded helically in usual manner to substantially circular compact section, then the strains of crushing, coming as necessarily they do unequally at 65 successive points upon the individual wires, produce deformation, and irregular deformation of the individual wires. The same wire is at different points in its extent differently misshapen and in many cases almost cut 70 through. One notable result of this rolling is that, electrically considered, the effective cross-sectional area of the conductor is greatly diminished. Therefore, the current-carrying capacity of the conductor as a whole 75 is greatly diminished—making it necessary to allow an excessive additional area of metal before rolling, to give the necessary required effective area after the rolling operation. The economies incident to the sector shape are 80 then partially or wholly lost in countervailing diminution of capacity.

Indeed, the difficulties here indicated are such that hitherto it has been impossible to produce a good sector-shaped conductor of 85 well-defined sector shape, composed of a bundle of wires of uniform cross-section and helically arranged,—a formation which, were it attained, would be of greatest value, because in it would be brought together many desirable features such as the following: well-defined sector shape, economy of space, maximum flexibility, and ability to be cabled with other conductors to a reasonably short cabling lay. 90

My invention consists in stranding the wires of the conductor (that is to say, bringing them together in a bundle in which the wires are helically twisted), the bundle itself being round, or approximately so. I 100 shall hereafter throughout this specification use the phrase "helically stranded" to designate the grouping of the wires in the manner indicated, and, in the drawings about to be described, clearly shown. The proportions 105 of this bundle are such—the arrangement of the component wires into a bundle is such, that the bundle itself may in an ensuing

operation be crushed to sector shape, and that without appreciably mutilating or misshaping at successive points the wires of which the bundle is composed. The resulting stranded conductor will be a stable entity, which will have a well-defined sector shape, which will have suffered little or no loss of effective conductivity incident to manufacture, and which will be free of localized hardening and deformation of its constituent wires. Also, the sector will have maximum flexibility both in torsion and in bending, and there will be little or no tendency of the sector to assume a rounded form when under torsion or bending. All this is accomplished without the employment of a core of straight-away wires or bars, to give the desired characteristic sector shape.

In the accompanying drawings Fig. I shows in side elevation and diagrammatically a collocation of wires helically stranded according to my invention into a bundle, the bundle being adapted to be crushed according to my invention from circular cross-sectional shape to sector shape. Fig. II shows the same collocation in cross-section. Fig. III shows the bundle after the crushing operation has been performed upon it. Figs. IV and V and VI and VII are pairs of correlated diagrams, corresponding to Figs. II and III, and illustrating the invention in further detail.

The invention consists essentially in stranding helically a number of wires to a bundle of hollow formation, preferably circular in cross-section, or substantially so, and then bringing the bundle to sector shape at the expense of the hollow space or spaces within the bundle; and this without mutilation of the component wires. In the bundle each wire is free of the others and in the shaping of the bundle the wires by virtue of such freedom may move, and do move, both laterally and longitudinally, and independently, to new relative arrangement, and there is no localized mutilation, no appreciable irregular diminution in cross-sectional area at successive points in the length of a component wire.

The area of a circle is greater than the area of a sector of equal periphery. If then a substantially or approximately circular bundle of tangent wires be formed with a hollow space within, and if such a bundle after being formed be brought to the cross-sectional shape of a sector of equal perimeter, the cross-sectional area of the bundle will be diminished. This diminution of area may be brought about wholly at the expense of the hollow space, and without appreciable mutilation of the individual wires irregularly at successive points in their length. My invention takes advantage of and realizes this possibility.

The simplest working out of the invention is attained in forming initially a hollow bundle of helically stranded wires. This simplest form is illustrated, with slight elaboration, in Figs. I-IV of the drawings. The bundle here consists of three successively enveloping layers of helically stranded wires (the number of layers is immaterial to the invention). The component wires of each layer are shown to be, and ordinarily will preferably be, tangent, or substantially so,⁷⁵ wire to wire. There is a hollow space within the innermost layer, and there are hollow spaces between the layers. Figs. I and II show the bundle when first assembled; Fig. III shows it when brought thereafter to sector shape. It will be observed, on comparing Figs. II and III that the hollow spaces initially present are ultimately eliminated. The bundle is in its initial stage (Fig. II) properly proportioned; each successive layer of wires is such in its extent, in the number of wires composing it, as to afford an inner space of proper size, so that when the sector shape is imposed upon the bundle the spaces will be diminished and preferably eliminated, the component wires will rearrange themselves and the component wires will closely overlie one another and the whole will become integrated in a unitary conductor, but without substantial mutilation of the component wires.⁸⁰

Another characteristic of the stranded, sector-shaped conductor of my invention is that it is susceptible to being twisted on its longitudinal axis without loss of its essential sector shape. This is a characteristic which has not hitherto been attained; hitherto it has been necessary, in making into a cable helically stranded sector-shaped conductors such as the art hitherto has known,¹⁰⁰ to assemble the component conductors in a very long "lay"; that is to say, with a very gradual twist or turning about the cable axis—a very much longer lay than otherwise would be employed. This limitation has been imposed by the circumstance that, if a shorter lay were attempted, the strains set up within the individual conductor would cause the component wires to shift in position, and the conductor as a whole to lose its essential sector shape. In the practice of my invention, the otherwise normal operation of cable making is not disturbed. The component conductors may be united with the desired relatively short lay, and that without loss of the essential sector shape of the component conductors. The result is a completed cable which is flexible in highest degree, in contrast with the relatively stiff structure which alone hitherto has been attainable.¹¹⁵

In building up the bundle diagrammatically shown in Fig. II mandrels may be employed, removable as building progresses; upon which mandrels the successive layers may be helically stranded. The mandrels for the out-¹²⁰ 125

er layers will of course be hollow. The crushing of the bundle, from the circular shape of Fig. II with included spaces, to the sector shape of Fig. III with spaces eliminated, may 5 be effected in any way known to the art, with the qualification, that the component wires shall be free to move longitudinally as well as laterally, one relatively to another. The crushing ordinarily will be effected between 10 rolls, one or both of the rolls being power-driven and the bundle of wires advancing in response to the tractive effect of the rolls upon it.

In Figs. I and II the successive layers are 15 shown standing in concentric arrangement, with no visible means of support. This concentricity will be substantially maintained, if the blank passes directly from the forming mandrels to the crushing rolls, with no 20 extended space between. But it will be understood that Figs. I and II may in this particular be taken to be diagrammatic. There can be no harm, nor disturbance of the described operation, if at the time when the 25 blank enters the crushing rolls the assembled layers do not stand concentrically, but instead rest one upon another at the lowermost points of their peripheries.

According to my present invention I carry 30 the crushing farther than to the point at which the component wires of the bundle are brought merely to tangency. That operation and its product are described and specifically claimed in my application Serial No. 35 185,096, alluded to above. For certain uses I have found that I may advantageously carry the crushing step further and may not merely eliminate the tubular space of the initial blank (leaving a finished product in which 40 the wires touch one another throughout the cross-section of the finished article), but I may, by carrying the crushing step further, shape the wires one to another, changing them from circular cross-section to more or 45 less completely polygonal cross-section. The individual wires in the finished article make tangency not along lines merely, but over facets produced by such further crushing. The result is a helically stranded sector-shaped conductor whose over-all dimensions 50 are less relatively to the effective cross-sectional area of conductor, when compared with a conductor produced by the method of my prior application; the resulting conductor has therefore characteristics which make 55 it useful, and under certain conditions preferable to any stranded sector-shaped conductor hitherto known.

Referring to Figs. I, II, and III, the tubular blank as here shown is (as ordinarily it 60 will be) multi-tubular, one tube being contained within another. Within each tube the helices in which the individual wires extend are turned all of them in the same direction and at the same pitch. It is

preferable that as between the several tubes the direction of turning of the helices shall be the same, and that the angle of pitch shall be substantially the same.

In forming from the blank of Fig. II the 70 product of Fig. III, I carry the pressure further. I not merely eliminate (as described above) the tubular spaces within the blank, but I compress the component strands beyond the point of tangency along lines. I change 75 the cross-sectional shape of the individual strands, I bring them to modified polygonal cross-section, and in the finished article the adjacent strands lie in tangency over extended surfaces. This will appear on comparing the Figs. II and III, and on considering individual wires *a*, *b*, *c*, *d*, and *e*. These wires initially are each of them round in cross-section. In the finished article these wires have been modified in cross-sectional 80 shape, and they abut one upon another over areas of substantial extent. Each is modified from circular cross-section to a polygonal cross-section, to this extent at least,—that there are between adjacent wires extended 85 areas of contact. As I have already explained, it is the freedom of the wires to adjust themselves within the bundle both longitudinally and transversely that makes possible the elimination of the tubular space 90 present in the original blank. It is this freedom of the wires to adjust themselves, and the fact that adjacent wires are laid in helices which extend in the same direction and at the same degree of turning that makes possible 95 this further crushing without loss in effectiveness of the finished article.

In this specific elaboration of my invention each individual wire is elongated. The cross-sectional area of conductor in the finished 105 article is less than the cross-sectional area of conductor in the blank. The crushing and elongation of the individual wire is, it will be remarked, an elongation which is uniform 110 from point to point throughout the length of the wire. It is this substantial uniformity in elongation from point to point throughout the entire length of each wire that is essential to practical success.

In Figs. IV and V, I have shown that if 115 the blank be a multi-tubular blank the successive tubes, instead of being spaced at intervals apart may be tangent. In this case the initial blank contains but one hollow space to be crushed out,—that which is found within the inner layer of wires. The crushing of the blank not only eliminates this space; but, as in the case already considered, it effects readjustment of the individual 120 wires and the crushing of the individual wires one upon another, modifying the individual wires in cross-sectional shape, causing them to assume a polygonal cross-sectional shape, with the sides of the polygons coincident, as between adjacent wires. In this 125 130

crushing operation the individual wires are elongated and the length of lay is increased, and, as between the two layers, the amount of elongation of individual wires is not exactly the same; but in these respects the individual wires of the bundle respond to the crushing strain, and the result is a sector-shaped bundle such as that shown in Fig. V, whose component strands of substantially polygonal cross-section are of substantially uniform cross-section throughout the length of the conductor, and whose component strands lie one against another in tangency over extended facets. The cross-sectional area of conductor in the finished article is less than the total cross-sectional area of conductor in the initial blank, but the ratio of cross-sectional area of conductor to total cross-sectional area is in the finished article very much greater than in the blank,—and very much greater than in any prior achievement in this detail of cable-making. Indeed, no article in the prior art includes a bundle so densely compressed, with its individual components of substantially uniform cross-section throughout its length. The last-named characteristic is, as I have said, of controlling importance. Since in the blank the component wires extend in helical course, in the finished sector every wire will extend in a course which is not straight-away, and a course which I characterize as winding.

In Figs. VI and VII a single tubular blank consisting of six wires is shown to be reduced according to the specific elaboration of my invention here under consideration to sector shape, and here the matter of the readjustment of the individual wires and the minute shaping of them may be more minutely considered, and the essence of my invention in its simplest form may there be studied and understood.

Turning now from the details of the several figures of drawing thus far considered to general observations, it is to be remarked that the angular value of the sector produced will be such as may be desired. The conductors shown in most of the figures of the drawings are intended for use in three-conductor cables, and the angular value of these sectors is 120° . If the conductor were intended for a four-conductor cable, the angular value would be 90° ; if it were intended

for a two-conductor cable, the angular value would be 180° . Such adaptations will be understood to be included in the contemplation of my invention and in the field of my patent.

The conductor built according to the foregoing description is assembled with other conductors and built into the finished cable. This will be done by the usual familiar operations, or their equivalents. It will be found that in the practice of my invention sector cables may be produced having large capacity, small dimensions, and flexibility, united in higher degree than hitherto has been attained.

I claim as my invention:

1. The method herein described of forming a stranded sector-shaped electrical conductor which consists in forming a tubular blank of individually free, helically stranded wires, each wire extending in a true helix, the turn of all of the helices extending in the same direction, and while the component wires are individually free to move both longitudinally and transversely with respect to adjacent wires crushing and elongating such blank and the component wires thereof and bringing the blank to sector shape with elimination of the tubular space within, and bringing the component wires to polygonal section with extended surfaces of contact between adjacent wires.

2. The method herein described of forming a stranded sector-shaped electrical conductor which consists in forming a multi-tubular blank of a succession of tubular layers, each layer consisting of individually free, helically stranded wires, each wire extending in a true helix, and the turn of all of the helices within the blank extending in the same direction, and while the component wires are individually free to move both longitudinally and transversely with respect to adjacent wires crushing and elongating the blank and the component wires thereof and bringing the blank to sector shape with relative rearrangement of the wires and with elimination of tubular space within, and bringing the component wires to polygonal section with extended surfaces of contact between adjacent wires.

In testimony whereof I have hereunto set my hand.

NORMAN C. DAVIS.
